UNITED STATES PATENT OFFICE.

JOHN B. VAN HOUTEN, OF NEWARK, NEW JERSEY.

DESIGN FOR AN EAR-RING AND PENDANT.

SPECIFICATION forming part of Design No. 14,519, dated December 25, 1883.

Application filed July 23, 1883. Term of patent 7 years.

To all whom it may concern:

Be it known that I, JOHN B. VAN HOUTEN, a citizen of the United States, residing at Newark, in the county of Essex and State of New Jersey, have invented and produced a new and original Design for Ear-Rings and Pendants; and I do hereby declare the following to be a full, clear, and exact description of the same, such as will enable others skilled in the art to which it appertains to make and use the same, reference being had to the accompanying drawings, and to letters of reference marked thereon, which form a part of this specification, of which drawings—

15 Figure 1 is a front elevation, and Fig. 2 a perspective view.

In said figures, the parts *a b c d* may be of any appropriate design, as the leading features of novelty are in the pendant portion of the ear-ring.

20 Of the pendant, *e* is a band-shaped portion, adjacent to which, at both sides thereof, the pendant is concavo-convex or bowl-shaped, as at *ff*, the bases or convexities of the bowl-shaped portions lying nearest the banded por-

tion *e*. The edges of the bowl-shaped portions are scalloped or indented, and from the centers of said bowl-shaped portions the pendant projects, forming button-shaped protuberances *g*.

30 The exact ornamentation and contour of the parts may be altered without materially departing from the spirit of the design.

What I claim is—

1. The design for an ear-ring pendant, as herein described and shown.

2. The design for an ear-ring pendant, the same consisting of a pendant having the band-shaped portion *e* and laterally-adjacent concavo-convex portions *ff*, the banded portion 40 of the pendant lying between the convex surfaces of the concavo-convex portions *ff*, as shown and described.

In testimony that I claim the foregoing I have hereunto set my hand this 19th day of 45 June, 1883.

JOHN B. VAN HOUTEN.
